BY
Decie C. Fischer
ATTORNEY

UNITED STATES PATENT OFFICE.

FRANZ A. FULLER, OF NEWARK, NEW JERSEY.

SHARPENING DEVICE FOR RAZOR-BLADES.

1,378,851.

Specification of Letters Patent. Patented May 24, 1921.

Application filed May 28, 1919. Serial No. 300,397.

To all whom it may concern:

Be it known that I, FRANZ A. FULLER, a citizen of the United States, residing in the city of Newark, in the county of Essex and State of New Jersey, have invented certain new and useful Improvements in Sharpening Devices for Razor-Blades, of which the following is a full, clear, and exact description, such as will enable others skilled in the art to which it pertains to make, construct, and use the same, reference being had to the accompanying drawings, and to numerals of reference marked thereon, forming a part of this specification.

15 The object of my invention is the production of a sharpening device for safety razor blades, which shall be simple and effective in construction, comparatively inexpensive in cost, and provided with securing means 20 to engage with corresponding means formed on a stropping device whereby the said sharpening device can be readily and conveniently secured to or removed from the stropping device, in order that the cutting 25 edge of the blade may be sharpened without removing the blade from the stropping device.

With this end in view, my invention consists in certain novelties of construction and 30 arrangements of parts, as hereinafter set forth and pointed out in the claims.

In the accompanying drawings,

Figure 1 represents, a side elevation of my improved sharpening device.

35 Fig. 2 represents, a front elevation of the same.

Fig. 3 represents, a rear elevation of the same.

40 Fig. 4 represents, a side elevation of a razor stropping device, in section, showing my improved sharpening device secured thereto and in operative position, and

Fig. 5 represents, a front elevation of the stropping device, a portion of the handle 45 being broken away.

Similar numerals of reference refer to like parts throughout the specification and drawings.

The razor stropping device illustrated in 50 the accompanying drawings, (forms the subject matter of patent application, Serial No. 280,982, filed March 6, 1919) is provided with receiving means to engage with corresponding receiving means formed on the 55 sharpening device, whereby said device can

be readily and conveniently secured to or removed from the stropping device, in order that the cutting edge of the blade may be sharpened without removing the blade from the stropper.

60 The said razor stropping device comprises a frame adapted to slide longitudinally of a strop, said frame comprising a body portion 1 and two opposite end portions 2—2 parallel each to each. A handle 3 is pivotally connected to the frame for permitting movement of the frame relative to the handle, and a blade holder 4 is rotatively connected to the said side portions of the frame. A roller 5 is also connected to said 65 side portions of the frame, and means are carried by said roller for transmitting rotary movement to said blade holder.

The body or frame of my improved stropping device may be stamped from sheet 70 metal or the like, and afterward bent into the desired shape as shown.

The front and rear longitudinal edges 75 6—6, of the body or frame are preferably bent upwardly to present bearing or guiding surfaces of the strop.

80 These bearing or guiding surfaces 6—6 are provided with receiving means which as illustrated are alined openings 7—7 formed near the side portions of the frame to engage with the receiving means formed on the sharpening device, to be hereinafter described.

85 The removable sharpening device, consists essentially of a hand operated roller 90 8 consisting preferably of stone or any other suitable honing or abrading material mounted on the rod 9, which is journaled in the two arms of the bracket 10. A handle 11 is also journaled in one of the arms of the 95 bracket 10 and has secured thereto the gear 17 designed to mesh with a gear 18 secured to the rod 9 and which serves to impart rotary motion to the roller.

100 The bracket 10 in which said honing or abrading roller is journaled may be stamped from sheet metal or the like and afterward bent into the desired shape as shown.

105 The lower edge of the bracket is provided with two parallel and outwardly extending tongues 12—12, designed to be received in the alined openings 7—7, formed in the front and rear longitudinal edges 6—6, of the body or frame of the stropping device, properly positioning the sharpening device. 110

A centrally arranged spring tongue 13 is also provided and which is preferably struck up and forms an integral part of the bracket, the front curved end of the tongue 5 being designed to snap over one of the longitudinal edges 6, and has holding engagement therewith, in this manner the device is locked to the stropping device frame.

Pivottally secured to the extreme upper 10 ends of the side portions of the bracket 10 are the side portions of a bracket 14 which may also be stamped from sheet metal or the like and afterward bent into the desired shape as shown.

15 To the inner surface of said bracket 14 in any desired or convenient manner, preferably by means of the pins 15—15, is secured a curved spring 16 extending lengthwise thereof.

20 This spring 16 is preferably made from a single piece of suitable material bent upon itself as clearly shown and designed to bear upon one side of the razor blade so that the required degree of pressure can be exerted 25 against the blade by pressing the pivoted bracket 14, by means of the operator's fingers, toward the roller 8.

To operate my sharpening device, it is only necessary to insert the integral tongues 30 12—12 of the bracket 10, into the aligned slots 7—7, in the body portion 1 of the razor stropping frame, thereby positioning the sharpening device, and then causing the curved end of the spring tongue 13 of 35 the bracket 10 to snap over one of the longitudinal edges 6, in order to lock the sharpening device to the frame of the stropping device.

The pivoted bracket 14 is then in the 40 position indicated in Fig. 4 of the drawings with the longitudinally arranged spring 16 bearing against the razor blade 19.

By pressing against the bracket 14 with the spring 16 bearing against the razor 45 blade 19 the desired degree of pressure can be exerted against the blade during the sharpening operation. Rotation of the roller by means of the handle will sharpen and polish the edge of the blade.

50 In order to remove the device from the frame, it only becomes necessary to disengage the spring tongue 13 from the longitudinal edge 6 and causing the tongues 12—12 to become disengaged from the openings 7—7.

I am aware that changes may be made in the several arrangements of the various parts, as well as in the details of construction thereof, without departing from the 60 scope of my present invention; hence I do not wish to be limited to the arrangements and combinations of parts as herein shown and described, as obvious modifica-

tions will suggest themselves to those skilled in the art.

65

I claim.

1. A device for sharpening razor blades, comprising a frame made from a single piece of suitable material, the lower portion of said frame being provided with integral means for securing said device to a frame carrying a razor blade holder, the upper portion of said frame being provided with integral brackets for supporting a roller, a sharpening roller rotatably mounted in said supporting brackets, a handle journaled in one of the roller supporting brackets, means carried by the handle and roller for transmitting rotary movement to said sharpening roller, and means to press a blade in said holder against said roller.

2. A device for sharpening razor blades, comprising a frame made from a single piece of suitable material, the lower portion of said frame being provided with integral means for securing said device to a frame carrying a razor blade holder, the upper portion of said frame being provided with integral brackets for supporting a roller, a sharpening roller rotatably mounted in said supporting brackets, a bracket pivotally secured to the outer portions of the roller supporting brackets, a spring secured to and extending lengthwise of said pivoted bracket and located in close proximity to the said roller, and adapted to bear upon the razor blade, a handle, means carried by the handle and roller for transmitting rotary movement to said sharpening roller.

3. A device for sharpening razor blades, comprising a frame made from a single piece of suitable material, the lower portion of said frame being provided with outwardly extending integral tongues for positioning and a centrally arranged integral spring tongue for locking said device to a frame carrying a razor blade holder, the upper portion of said frame being provided with integral brackets for supporting a roller, a sharpening roller rotatably mounted in said supporting brackets, a bracket pivotally secured to the outer portions of the roller supporting brackets, a spring secured to and extending lengthwise of said pivoted bracket and located in close proximity to the said roller, and adapted to bear upon the razor blade, a handle, means carried by the handle and roller for transmitting rotary movement to said sharpening roller.
